UNITED STATES PATENT OFFICE.

THOMAS I. RANKIN, OF PHILADELPHIA, PENNSYLVANIA, ASSIGNOR TO THE ABRAM COX STOVE COMPANY, OF SAME PLACE.

DESIGN FOR A COOKING-STOVE.

SPECIFICATION forming part of Design No. 29,589, dated November 1, 1898.

Application filed September 27, 1898. Serial No. 692,031. Term of patent 8½ years.

To all whom it may concern:

Be it known that I, THOMAS I. RANKIN, a citizen of the United States, residing in Philadelphia, Pennsylvania, have invented and 5 produced a certain new and useful Design for a Cooking-Stove, of which the following is a specification.

My design for a cooking-stove is clearly illustrated in the accompanying drawing, the 10 figure of which represents the stove in perspective.

The essential feature of the design is the 15 figured panels of the base and the peculiar figuring of the several doors.

The base M has a fan-shaped scroll *m* at each corner, with a ribbed center *m'*, and extending down each leg are scrolls *m''*. Along the apron of the base are a series of independent figures *n*, each consisting of a border 20 within which is a floral scroll, the center figure being double, as illustrated.

The oven-door P has a plain panel at the center, surrounded by a border made up of a series of scrolls, and at the base of the panel 25 is a fan-like scroll. At each side of the central panel are elongated scrolls extending the height of the door, and these long scrolls are connected together by short scrolls extending over the panel.

The fire-door Q is ornamented in the peculiar manner illustrated, having a central figure 30 with scrolls extending from the upper portion and a scroll at the base.

The ash-pit door R has a central figure with scrolls extending from each side. 35

The back plate S, mounted above the top plate of the stove, consists of a central oval ornament *s*, with elongated **S**-scrolls *s'*.

I claim—

1. The design for a cooking-stove as herein 40 described and as shown in the accompanying drawing.

2. In the design for a cooking-stove, the base as herein described and as shown in the 45 accompanying drawing.

3. In the design for a cooking-stove, the oven-door as herein described and as shown in the accompanying drawing.

4. In the design for a cooking-stove, the fire-door as herein described and as shown in 50 the accompanying drawing.

5. In the design for a cooking-stove, the ash-pit door as herein described and as shown in the accompanying drawing.

6. In the design for a cooking-stove, the 55 back plate as herein described and as shown in the accompanying drawing.

In testimony whereof I have signed my name to this specification in the presence of two subscribing witnesses.

THOMAS I. RANKIN.

Witnesses:

WILL. A. BARR,
JOS. H. KLEIN.
